John A. Gray administrator of Amos B. Bull's estate

Letters Patent.

The Schedule, referred to in these Letters Patent, and making part of the same, containing a description in the words of the said John A. Gray himself, administrator of Amos B. Bull, deceased, of his Amos B. Bull's improvement in the tray for the cure of relaxation of the Vagina, and prolapsus of the Uterus.

To all to whom these presents shall come. Be it known that as Amos B. Bull, late deceased, of the city of New York, in the County of New York, and State of New York, did in his lifetime, invent a new and useful improvement on his tray or instrument for the cure of relaxation of the Vagina, & prolapsus, of the Uterus patented on the seventh day of May eighteen hundred and thirty four. The improvement consists in the adaptation of this tray, in combination with a stiffer or pessary of a peculiar form, & construction, to produce the necessary pressure on that lower part of the belly, between the thighs known in surgery by the name of Perineum; so as that the pressure shall be retained in the Vagina, in the position required, & with sufficient strength to resist that effort commonly considered as a inclination of the womb; the retention to be effected by the assistance of the strings (in the old tray as above mentioned) which is sustained between the thighs, pendant from the abdominal & back parts; having by its material or whether cloth or gum elastic, sufficient elasticity to give any desired pressure. It is known that an instrument called a pessary, has been long in use & variously constructed, but that mode which is now here described, was invented and particularly adapted by the peculiarity of its construction, to the purpose for which it was designed by forming it into a cylindrical shape A of say from one & a half, or to about three inches long by from one half, to about one inch in diameter, though of course these dimensions will be suited to the patient. It is

to be

1864

to be composed of sponge, or gunn elastic, or other pliable elastic substance. If the sponge is adopted, then a case is to be made of vulcan or vulc-like substance, to enclose it, and by being compressed therein, in a dry state will contract the advantage to be obtained by the expansion of it in the case, concomitantly with a firmness to be wished for. The ends of the case may be drawn together, so as to produce there a flange, having the edges concaved toward which can be effected conveniently by means of them, a running string, or, if gun elastic is used, then it may be moulded or cast into the desired form, making a solid body throughout. This form of preservy, when so constructed, is to have suspending from the end which will be nearest to the entrance of the vagina, a small cross cord or string B, for the purpose of withdrawing it when necessary, and also for retaining it in its proper position, that it may not be deranged, which is effected by connecting the string at a slight tension with the loop C of the tube passing between the fingers. Now, in the application of it, care must be taken, that it is well lubricated & carefully introduced into the vagina according to surgical rules. The string is now to be connected to the elastic strap of the tubes; which, passing between the fingers, is suspended from one strap C, to the other F, and this strap being drawn tight as required, presses up the perineum, and suffices sufficiently, the necessary contraction lost by under relaxation of the muscle membrane of that part. It must be seen that this necessarily keeps the preservy pressed up against the upper part of the vagina and retains it there immovable against the pressure from above, or from the direction of the womb H, and consequently effects the support of that organ, in its proper position, as long as required. To medical men the facility with which ^{the} preservy can be withdrawn as often as needed, the slight risk of infection from excrements deposited accidentally, as well as the certainty of its not producing the injurious effects of the sucking of the lower part of the vagina, beneath the weight of the circular or ring preservy, as in the old practice, will prevent most advantages.

advantages to be gained by the patients, in the ease & comfort attending this mode of application. Another manner adopted, was to apply a triangular shaped long wedge J, to the inside of the strap, so as to bear upon the perineum from without, or externally; and then dispense with the internal pressure. The effect of the pressure will be the same. Or, again, to employ a flat spring J, to descend from the front pad reaching the same part, to communicate the desired pressure with the same effect. Or else, to use a round spring K, to descend from the back pad to the part, and still convey the same effect, the roundings intended to obviate inconvenience in sitting. All of these modes tend to produce the main effect contemplated by the aforesaid Amos G. Hull, viz., that of affording such support by means of the strap, to the related vagina as would produce through the agency of the pressure or the wedge a proper support to the pressure from the uterus above, which will form the characteristic distinction of his principles of application by the modes above shown; as shall enable any competent professional persons to distinguish the said modes, as distinct from those of the practitioners. Now what I claim, is not heretofore used or known, & as the invention of my father in law, the said Amos G. Hull, deceased, and for which I now ask Letters Patent, is the manner of application of support against the relaxation of the vagina, & descent or prolapse of the uterus according to the modes or methods above set forth; viz. First, the mode of construction and shape or form used in the harness according to the principles for the use above set forth. Second - The application of the harness as described, combined with the support obtained from the elastic strap as already explained. Third - the mode of applying the wedge externally, by means of the strap, for the same effect as shown. Fourth - the manner of application, by means of the springs, either round or flat, as already stated.

See testimony that the above is a full description of the improvements made by the said Amos G. Hull before his

his release, on his previous trip. I have this day
set my hand this thirty first day of October in the year
eighteen hundred and thirty five.

Very sincerely

W. F.
